Primary Examiner — Philip S Hyder*Assistant Examiner* — Roselynne Ulm Cody(74) *Attorney, Agent, or Firm* — Nancy J. Flint, Esq.; Nancy J. Flint, Attorney At Law, P.A.(57) **CLAIM**

The ornamental design for a drywall sheet removal tool, as shown and described.

DESCRIPTION

FIG. 1 is a left front perspective view of a drywall sheet removal tool according to my new design;

FIG. 2 is a front view of a drywall sheet removal tool according to my new design;

FIG. 3 is a back view of a drywall sheet removal tool according to my new design;

FIG. 4 is a left side view of a drywall sheet removal tool according to my new design;

FIG. 5 is a right side view of a drywall sheet removal tool according to my new design;

FIG. 6 is a top view of a drywall sheet removal tool according to my new design; and,

FIG. 7 is a bottom view of a drywall sheet removal tool according to my new design.

Any broken line illustration of environmental structure in the drawings is not part of the design sought to be patented.
